UNITED STATES PATENT OFFICE.

HIRAM M. BURDICK, OF ILION, NEW YORK.

HORSE HAY-RAKE.

SPECIFICATION forming part of Letters Patent No. 339,971, dated April 13, 1886.

Application filed April 17, 1885. Serial No. 162,587. (Model.)

To all whom it may concern:

Be it known that J. HIRAM M. BURDICK, a citizen of the United States of America, residing at Ilion, in the county of Herkimer 5 and State of New York, have invented certain new and useful Improvements in Horse Hay-Rakes, of which the following is a specification, reference being had therein to the accompanying drawings.

10 This invention pertains to improvements in horse hay-rakes, and has for its object to provide means for holding the rake down to its work as against being accidentally forced upward therefrom, the ready and easy actuation 15 of the elevating or dumping contrivances of the rake, and to vary the height of the elevation of the rake, when under the action of the pawls, by effecting the disengagement of the pawls with their ratchets; and to these ends 20c the invention consists of the combinations of parts and their construction, substantially as hereinafter fully set forth, and pointed out in the claims.

In the accompanying drawings, Figure 1 is 25 a plan view of my rake. Fig. 2 is a sectional elevation thereof, the section being taken at the juncture of a wheel-hub and its ratchet. Fig. 3 is an enlarged detailed view of one of the adjustable rake-head-trip appliances or 30 mechanism. Fig. 4 is a cross-section of the rake, showing more clearly the rake elevating or dumping contrivances, together with its retaining and lowering mechanism; and Figs. 5, 6, 7, 8, and 9 are detail views.

35 In the embodiment of my invention, with a view to carry out the aforesaid objects, I support the rake-head A, to which is applied at its ends disks a, upon short axles b, bearing wheels B and cast with the disks, said disks 40 also being cast with brackets b', each comprising a front vertical plate and a bottom horizontal plate, which plates are bolted to the rake-head, so that the ends of the latter abut or rest against the disks. Upon the inner 45 sides of the wheel-hubs are cast or made fast thereto ratchets d, while between the wheel-hubs and the disks a are disposed pawls C, with their lower hooked ends engaging the said ratchets, said pawls being made fast to 50 the ends of a continuous rod, D, passing through an aperture in each disk a, and sup-

ported about centrally of its length in the side pieces of a casting or bracket, e, fastened to the front side of the rake-head, which parts will be again referred to further on.

55 The curved teeth A' of the rake are articulated or pivoted to a common rod, a', inclosed in the rake-head A, said teeth extending, as usual, through the rear side of said head and through a common supporting-bar, b', arranged a short distance in rear of and firmly connected, preferably by curved or approximately inverted-U-shaped brackets or arms d', to the rake-head, said brackets being screwed or bolted to the rake-head and bar 65 b', while the bar b' is provided with vertical slots b'', for the passage through it and to permit the independent movement of each tooth, (except as hereinafter named,) for their escape from obstructions. To two central rake-teeth, 70 near their lower ends, is fastened a piece of heavy metal, d'', to weight the lower end of and aid in holding the rake to its work.

75 Ordinary fingers or bars, e', are fastened to the draft-frame E, and project rearwardly therefrom sufficiently to eliminate or remove the gathered or raked hay from the rake-teeth as the rake is elevated or dumped.

The draft-frame E, having the thills E and supporting the seat E', is pivoted or connected 80 to pivots or projections f, cast or fast with the disks a, and supported near their outer ends in brackets f', depending from the castings or brackets b' of the rake-head, said pivots or projections f being fast to the said disks and 85 passed through apertured thill-irons g, fastened to the draft-frame E. Upon these thill-irons are disposed, so as to be adjustable, the plates g' of the rake-head-tripping device, which is more especially adapted to automatically limit the upward and forward movement or elevation of the rake or its head when actuated by the pawls alone, said plates g' having pendants g'', against which strike lateral projections or pins h, projecting from the pawls 90 C, through slots of the disks a.

95 The adjustability of the plates g' is effected by means of screws g'', passing through slots g''' of said plates and entering the thill-irons, the purpose of which is to allow of the adjustment of the said plates so as to permit their pendants g'' to intercept the movement of the 100

pins or projections *h* of the pawls *C*, retracting or disengaging the pawls from their ratchets at different points in the upward movement of the rake, whereby the height of the 5 elevation of the latter can be varied as may be required.

Again referring to the rod-connection *D* between the pawls *C*, it will be seen that a pendent bar or arm, *F*, is screwed or rigidly bolted to 10 said rod or connection between the side pieces of the casting or brackets *e*, which arm or bar is connected by an eyebolt or equivalent device to a rod, *i*, with its outer forward end connected to the lower end of the lever *G*, as 15 presently more fully described.

The pendent bar or arm *F* is acted upon by a spring, *j*, inclosed in a tubular or thimble-shaped extension of the bracket *e*, said extension being arranged under the rake-head. 20 The normal action of the spring *j* is to cause the arm or lever *F* to so act upon the rod *D*, when the pawls are not in use, as to automatically retract and hold retracted the pawls from their ratchets, while by pressing inwardly upon 25 the said lever *F* at its lower end, which is effected through the lever *G*, the rod *D* will be so acted upon as to put the pawls into engagement with their ratchets, the effect of which latter action of parts is to cause the 30 turning or revolving of the rake-head, and consequently effect the elevation of the rake and the dumping of its contents, it being assumed, of course, that the machine is in motion.

35 The lever *G*, whose upper or actuated end is provided with a lateral bend or arm, *G'*, to permit of its convenient actuation by the foot, is pivoted a short distance above its lower end to a rear extension or arm, *k*, of a shoe, *H*, 40 brazed or cast at its inner side with a rocking or tilting lever, *I*. The rear end of the lever *I* is provided with a forwardly-projecting hook, *l*, while near its forward end it is pivoted to a bracket or casting, *J*, bolted to the 45 draft-frame. The said forward end of the rocking lever *I* is rounded upon its upper edge or surface or otherwise adapted to permit of the convenient operation of the lever or its hooked end by the action of the foot upon said 50 forward end. The bracket or casting *J* is provided with a shoulder, *m*, just below the lever *I*, to limit the downward movement of the latter when actuated.

To the rear end of the casting or bracket *J* 55 is pivoted at its lower end a link or bar, *K*, and in the slot formed in the upper end of said link or bar is pivoted near its end a link, *k'*, which is connected at its other end to the rear side of the rake-head, the connection therat 60 being formed by passing the pivot at that end through apertured lugs of a bracket, *m'*, bolted to said side of the rake-head. The outer end of the link *k'*, beyond the point where it is pivoted to the link or bar *K*, is slightly inclined, so that when the rake is elevated the 65 same will occupy a horizontal position, and on the upper end of this inclined portion is se-

cured a foot-rest, *K'*, the purpose of which will appear farther on.

The foot-lever *K* is provided upon that side 70 next to the hooked lever *I* with a projection or pin, *n*, which, when the foot-lever *K* is thrown forward to elevate or dump the rake, may be caught by the hook *l* of the lever *I* when it may be desired to retain the rake elevated without exerting the continuous pressure or action of the foot upon the foot-lever. In order, however, to cause the engagement 75 of the hook *l* of the lever *I* with said pin *n* of the link *K*, either the rocking lever *I* or its 80 shoe *H* will have to be actuated or tilted forward, permitting the hook to catch over and hold the pin.

It will be observed that by reason of the capability of the rod-connection *D* being adapted 85 to have a more or less twisting or torsional action, as it in practice does, the pawls will be allowed to slip by the teeth of the ratchets should the pawls happen to be held upon the turning of the rake after dumping unintentionally or inadvertently in engagement with the ratchets by the failure of the driver or operator to release or remove his foot from the lever *G*.

In order to commence work, the driver or 90 operator, being seated upon the machine, places and holds his right foot upon the foot-lever *k* *k'*, placing it upon the foot-rest *K'*, and starts the team, drawing the machine over the ground, the driver at the same time pressing 95 upon the foot-lever, enabling the rake to gather or rake up the hay. After a sufficient quantity of hay has been gather or raked up, the driver or operator swings the heel of the foot used in pressing upon the shoe *H* of the lever 100 *I* to and upon the bend of the lever *G*, his toe resting upon the shoe *H* of the lever *I*, and presses forward upon the lever *G*, which will 105 actuate the rods *i* and *D*, when the latter rod will apply the pawls *C*, causing the revolving 110 or turning of the rake-head and the elevation or dumping of the rake. The rake having been dumped, the operator removes his heel from the lever *G*, the pawls, the instant 115 this is done, being released from the ratchets, and the rake will by its own weight or gravity return to its normal lowered position. If, however, it is desired to retain the rake elevated, the heel is swung back upon the shoe 120 *H* of the foot-lever *I* and the toe placed and pressed upon the forward end of the shoe of the lever *I*, tilting the latter forward when the hook *l* of the said lever *I* will catch over the pin or projection *n* of the lever *K*, locking the parts together and holding the rake elevated 125 without other assistance.

In order to lower the rake when held as above described, press upon the foot-lever *K*, when the hook *l* of the lever *I* will instantly release the pin *n* of the said lever *K*, and lessening the pressure of the foot upon the latter lever the rake will return to its lowered position.

It will be seen that should the operator fail

to remove his foot from the lever G, when the same has been so acted upon as to cause through the rod i and rod-connection D the engagement of the pawls with the ratchets 5 and hence the elevation of the rake, when the rake has been elevated to its maximum height, to cause the disengagement of the pawls with the ratchets, the same is effected by means of the pins or projections h of the pawls abutting 10 against the pendants g of the plates g'.

Having thus fully described my invention, what I claim, and desire to secure by Letters Patent, is—

1. In a horse hay-rake, the combination, 15 with the pawls engaging with the ratchets on the wheel-hubs and connected at one end by a rod-connection, and having on their other ends pins or projections, of the adjustable plates having pendants at their rear ends, the 20 thill-irons, and the end disks having pivots or projections for connection with said thill-irons, said disks being slotted for passage of said pins or projections, substantially as shown and described.
2. In a horse hay-rake, the combination, 25 with the lever G, the spring-actuated bar or arm, and the rod-connection D, said lever connected to said bar or arm by rod i, of the pawls connected to each end of said rod-connection having a lateral projection or pin on their outer ends, and the end disks having slots for passage of said projections or pins, and the adjustable plates having pendants at their rear ends, said end plates having pivots or projections for connection with the 30 thill-irons, substantially as shown, and for the purpose specified.

3. In a horse hay-rake, the combination, with the spring-actuated bar or arm and the lever having a rod connecting with the lower 40 end, of said bar or arm of the rod-connection, the pawls engaging with ratchets on the wheel-hubs and carrying pins or projections, and the adjustable plates having pendants at their rear ends, said pawls being connected at one 45 end to said rod-connection, substantially as shown and described.

4. In a horse hay-rake, the combination, with the supporting-wheels having ratchets on their hubs, of the rake-head, a rod mounted 50 thereon, pawls engaging said ratchets and secured to said rod, a pendent arm on said rod, a spring lying in a tube connected with the rake-head and bearing against said arm, a lever connected to said arm by a connecting 55 rod and fulcrumed to a lever provided with a foot-rest and hooked end, and a tilting lever adapted to engage said hooked end, substantially as shown and described.

5. In a horse hay-rake, the combination, 60 with the end disks and the pawls having pins or projections passing through slots of the said disks, of the adjustable plates having pendants at their rear ends, substantially as shown and described. 65

In testimony whereof I affix my signature in presence of two witnesses.
